HYDRAULIC PUMP

Roger F. Horton, Hempstead, N. Y.

Application February 28, 1945, Serial No. 580,142

8 Claims. (Cl. 103—161)

1

This invention relates to an hydraulic pump. An object of the invention is to provide a simple, economical and efficient hydraulic pump adapted for operation at high pressures.

Another object of the invention is to provide an hydraulic pump having less internal friction and therefore less power loss within the pump than has heretofore been attainable.

Another object of the invention is to provide a high speed hydraulic pump having a greater horsepower output per pound of weight than has heretofore been available.

Another object of the invention is to provide means for increasing the centrifugal energy of low pressure fluid revolving within the pump casing and to eliminate the need for separate booster pump means to fully fill the cylinders of the cylinder block at high speed.

Another object of the invention is to utilize heretofore unused means without further complicating the mechanism for supplying the fluid to the rotor cylinders with increased energy.

Another object of the invention is to provide an hydraulic pump readily adapted for opposite hand rotation of the rotor.

Another object is to provide an hydraulic pump in which internal friction is greatly reduced by the substitution of rolling friction for sliding friction, thereby permitting higher speeds and higher loading per square inch of bearing surface.

Another object of the invention is to provide an hydraulic pump which is capable of higher speeds than have heretofore been attainable by prior art pumps without the aid of separate booster pump means.

Another object of the invention is to provide means for pumping more fluid at higher pressure with less weight and size, at higher over-all efficiency.

Other objects of the invention will be in part obvious or in part pointed out hereinafter.

This invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a front elevation of an embodiment of the invention, taken on the line 1—1 of Figure 2, partly cut away and partly in vertical section;

2

Figure 2 is a side elevation taken on median line of Figure 1 in a plane passing through the axis of the pump, partly cut away and partly in section;

Figure 3 is a longitudinal sectional view of the pindle indicated in Figures 1 and 2, showing its connecting fluid ports and conduits;

Figure 4 is a vertical transverse section taken on line 4—4 of Figure 3;

Figure 5 is a front elevation, partly broken away and partly in section, showing the path of the fluid;

Figure 6 is a side view, partly in longitudinal section and partly in dotted lines, showing the relation of the pump parts and the path of the fluid;

Figure 7 is a detail view in vertical section showing the unbalanced nature of the frictional contact between the respective pistons of the radial cylinder block and a grooved surface of the track ring;

Figure 8 is a plan view of the detail shown in Figure 7;

Figure 9 is a detail view of one of the track 25 ring supporting members shown in Figure 2;

Figure 10 is a side view of a section of the member shown in Figure 7.

In the following description the term "drive end" is used with respect to elements of the 30 pump to indicate the end which is nearer or extending toward the mechanical input side of the pump, and the term "anti-drive end" is used to indicate the end extending toward, or which is nearer, the hydraulic high pressure output side 35 of the motor.

My hydraulic pump comprises a closure which may have a combined casing 10 and mounting flange 11, and a casing cover 12, the cover 12 being joined to the casing 10 as by machine 40 screws 12a. The casing cover 12 is provided with a central bore into which extends the pindle 13 having the flange 13a overlying the outer face of casing cover 12 and being secured thereto by the studs 14 and nuts 15 respectively. Pindle 13 has 45 at its drive end a wearing plug 16 which abuts against wearing plug 17 fixed in the anti-drive end of the hollow drive shaft 18 which carries at its other extremity the pump driving spline 52.

The pindle 13 is provided with two longitudinally 50 extending bores 19 and 20 respectively, which are closed at the drive end but open at the anti-drive end. The bores 19 and 20 respectively, adjacent the drive end of pindle 13, are internally threaded to receive the externally threaded plugs 21 and 55 22 respectively. Bore 19 is provided with a port

23 extending radially through the pintle shell, and bore 20 is provided with a port 24 extending radially through the pintle shell, and spaced substantially 180° around the pintle surface from port 23. Bore 19 is also provided with port means, spaced toward the anti-drive end of the pintle from port 23 and adapted to register with conduit 26 which extends through the wall of casing cover 12, from mouth 53 at the inner periphery of the casing to its outlet which is in register with the pintle surface. As shown this port means comprises the two peripherally spaced ports 25^a and 25^b, separated by the web 25^c. The ports 25^a and 25^b serve to communicate with bore 19 at all times the particular one of these bores which will intercommunicate between the outlet end of conduit 26 and bore 19 depending upon the direction of rotation of the cylinder block for which the pintle is set, one setting being 180° removed from the other setting as will be explained.

Revolvably mounted on pintle 18 is a rotor assembly 27 (Figure 2) comprising the radial cylinder block 28 having cylinders 29, preferably seven in number, in the bores of which pistons, 28, are freely mounted, so that they are slideable and also rotatable about their respective longitudinal axes, said pistons being provided with generally spherical heads 30, having a small relief or flat area 31, at the top of the dome, adapted to prevent contact between the extreme top center of the piston head, and a groove 32, provided in the inner surface of track ring 33, and into which said pistons 29 extend. Preferably the radius of the spherical head of the pistons and the radius of the groove 32 is substantially the same. That is they ideally have the same radius allowing for the tolerance inherent in the machining of their parts. The resulting contact between pistons 29 and track 33 is a rolling contact, due to the extremes of the heads being relieved, and because, as I found in a practical embodiment of the invention, the friction forces due to contact on diametrically opposed sides of any of said pistons are unbalanced due to variations in tolerance, which, at the present time with present manufacturing tools, are inevitable and unavoidable. Accordingly there will be in practice a frictional force F on one side of the piston center, greater than the theoretically balanced forces f (Figure 8), causing pistons 29 to rotate within their respective cylinders about their own axes respectively as well as rotating about the pintle with the cylinder block during their reciprocal action, as shown in Figures 1 and 2, and thus have predominantly a rolling contact with the track ring which also rotates about the pintle at speeds approximately those of the rotor.

Track ring 33 is supported by radially extending supporting members 34 and 35, arranged in opposed, laterally spaced relation, and by the bearings 36 and 37 respectively, positioned concentrically around the outwardly extending flange portions of the members 34 and 35 respectively, which are seated respectively in bores eccentric to the pintle and cylinder block and provided in opposed relation in the inner faces of casing 10, and casing cover 12, respectively. The radially extending support members 34 and 35 are provided with outwardly opening radial slots 51 to be described.

At the drive end of radial cylinder block 28 the circular flange 38 is bored to provide a circle of spaced holes extending parallel with the cylinder block axis, and the internal face of flange 38 is

then ground out to convert the holes, throughout a portion of their depth, into the half holes or semi-cylindrical bores 38^a. A similar circle of holes is provided in the abutting end of radial flange 39 of drive shaft 18, and flange 39 is ground externally to similarly convert the said holes, throughout a portion of their length, into the half holes or semi-cylindrical bores 39^a, the diameter of radial flange 39 of the drive shaft being related to the diameter of the flange 38 of the cylinder block so that the half holes of flange 39 may complement the half holes of flange 38 to form complete cylindrical spaces, and in these spaces cylindrical pins 40 are inserted. There is thus provided a large diameter high torque spline between cylinder block 28 and drive shaft 18 by which the drive force is transmitted to the latter from the former, and with a minimum of friction in the event of axial misalignment for any reason.

Extending around drive shaft 18 and serving to retain it in position of engagement with driving pins 40 of the cylinder block 28 is a coil spring 41, which is retained between the drive shaft flange 39 and a collar 42 extending around the driving shaft and turning with it. Suitable packing 43 may be provided between collar 42 and shaft 18, and also suitable packing may be provided between the collar 42 and end plate 44 secured to mounting flange 11 as by screws 44^a. Preferably packing 43 is of an oil resisting material such as neoprene. The packing between collar 42 and end plate 44 may desirably comprise a ring 45 of morganite or bronze having a lapped surface pressed against the lapped surface of a ring 46 of cast iron by action of collar 42. Preferably also an oil seal 47 is provided between the mounting flange 11 and the end plate 44.

As shown in Figure 3 fluid is supplied to the pump 10 through conduit 48, which communicates with the open end of a conduit 49 extending through the wall of pintle flange 13^a, and which in turn communicates with a port 50 extending through the wall of casing cover 12 and adapted to lead fluid into the interior of the casing into the space therein surrounding cylinder block 28. The track ring support members 34 and 35 are provided with outwardly opening radially extending slots 51 (Figure 7), the open ends of which point toward the periphery of the casing. Fluid is supplied into the pump casing through conduit 50 and flows into and fills the space surrounding cylinder block 28, and fills the radial slots 51. The cylinder block 28 and the track ring assembly are of course driven by power which is applied at spline 52, and which is transmitted to the cylinder block through the drive shaft 18 and the cylindrical pins 40 interconnecting the drive shaft and the cylinder block. As the cylinder block and track ring assembly rotate fluid, entering into the pump casing through port 50, from conduit 49 through the pintle flange 13^a, and supply conduit 48 successively, fills the radial slots 51 and is discharged from said slots by centrifugal force engendered by the rotation of the cylinder block and track ring assembly. The fluid thus forcibly discharged from slots 51 adds to the centrifugal force of the fluid in the casing which is thus supplied at increased speed into the mouth 53 of conduit 26 which leads back to port 25 of the pintle. Fluid entering into the interior of the pintle through port 25 passes axially through bore 19 and is discharged therefrom through port 23 which communicates through the interior of radial cylinder block 28 with the inner ends of

5

the bores of the cylinders 28 respectively, the pistons 29 for said cylinders respectively being, at the time of communication with said port 23, at substantially the end of their outward travel, due to the eccentricity of the axis of the track assembly with respect to the pintle axis. The incoming fluid will thus flow into the cylinders successively at low pressure and will in turn be forced out of the cylinders at high pressure by the return stroke of the piston members respectively, and discharged through pintle port 24 into the pintle bore 20 and the discharge passage 54 through which the fluid, now at high pressure, is delivered to perform the desired work.

The direction of rotation of the cylinder block 15 of the pump disclosed herein may readily be reversed. For this purpose a port 50a, similar to port 50, is provided through the wall of the casing but substantially 180° removed from port 50. For opposite hand rotation it is only necessary to remove nuts 15 and studs 14, which secure pintle flange 13a to casing cover 12, and rotate the pintle 180° with respect to the pump casing and its cylinder block and track assembly, thus changing by 180° the angular position of the cylinders when they are charged, and thus reversing the direction of rotation of the cylinder block. The pintle flange may then again be secured to the casing cover and the opposite hand rotation of the pump may be continued as long as desired, the operation being the same as that described above except that fluid supplied to conduit 49 through conduits 48 will enter the casing through port 50a instead of through port 50.

Radial slots 51 are provided in support members 34 and 35, as stated above, to add centrifugal energy to the fluid supplied to the cylinders from the casing for the purpose of completely filling the displaced volume in the cylinders during each piston stroke, and thereby make up for the loss of energy occurring between the reservoir and the pump cylinders and to increase the maximum velocity and speed at which the fluid may be supplied from a fluid reservoir to the casing and from the casing to the cylinders of the cylinder block. In this way a volume of fluid sufficient to completely fill the cylinders at all speeds, may be supplied to the cylinders at increased pressure for conversion from low pressure to high pressure, thereby making it unnecessary to use accessory supercharging pumps which are commonly used with piston type pumps.

Since the slots 51 are an integral part of the design of my pump they can be modified as to size and number so that the fluid delivery characteristic of the pump can be made to exactly fit the requirements of the pump at all speeds. A supercharging pump is not only an accessory and an additional piece of equipment and therefore undesirable but it has its own limitations and they limit the main pump, but this is not the case with my integrally formed supercharging means provided by slots 51.

It will be noted that by the provision of slots 51 I have not only added increased energy to the fluid supplied to the pump cylinders but in so doing I have utilized energy which has heretofore been wasted.

Since the fluid within the casing, and particularly the portion which is radially beyond the track ring 33, is rotating with the track ring and the ring supporting members 34 and 35, prior to discharge, the force with which the fluid is supplied to mouth 53 of conduit 26 can be calculated from the formula $F = Mr w$ where M =mass of

6

fluid under consideration; r = the distance from the mass center of the fluid to the center of rotation; and w =the angular velocity of this mass center about the center of rotation.

In order to increase the volume of force F I increase all elements in the above equation by proper arrangement of radial slots 51, the eccentric center of track ring 33, and the mouth 53 of conduit 26. It will be seen by reference to Figures 1 and 6 that this is accomplished as follows: The center of the mouth 53 of conduit 26 and the eccentric center, a , of the track ring, are located on diametrically opposite sides of the center, b , of the pintle. This arrangement provides in effect two semi-circular complementary chambers c and c' , which together completely encircle the track ring 33, and which are identical in size and shape, each having a constantly increasing mean radius. Only one of these chambers is active in adding centrifugal force to the fluid within the casing for each direction of rotation of the rotor assembly. The constantly increasing mean radius of the chamber which is active, and into which fluid is continuously being forced by the radial slots 51, provides a constantly increasing M , or mass, as the fluid approaches the mouth 53 of conduit 26, and also provides a constantly increasing r . Since w is a function of r , w is also constantly increasing. Thus three factors in the equation are constantly increasing, from a minimum at a point diametrically opposite the said mouth 53 to a maximum at the mouth itself. In addition to this arrangement the size and number of the radial slots 51 can be determined so that fluid is thrown out of them into the chamber which is active in building up centrifugal force in a volume proportional to the chamber's increase in volume, and consequently the supercharging pressure increases in proportion to the pump speed. Thus, there is provided a simple and effective centrifugal pump specially designed to increase the flow of fluid to the working cylinders of a given pump, making it possible for them to perform more net work.

The hydraulic pump described herein has the great advantage that it may be embodied in a unit of small size. The pump due to the elimination of sliding members and resultant decrease of friction is characterized by increased efficiency per pound of pump weight as compared with prior art hydraulic pumps.

It will thus be seen that there has been provided by this invention an apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What I claim is:

1. In a radial pump, a casing, a pintle mounted centrally in the casing, and a rotor assembly rotatable in said casing around said pintle including a radial cylinder block, a track ring, means for supporting the track ring comprising members positioned on opposite sides of the rotor each having an annular, radially extending disk-like portion and a hub portion, said casing having bearings to receive said hubs respectively, said disk-like

portions having their outer peripheries in inter-engagement with the sides of the track ring respectively, said pintle having two axially extending bores and two circumferentially spaced ports communicating between said bores respectively and the interior of said cylinder block, and having a third port communicating with one of said bores, and spaced axially of the pintle from said other ports, a conduit extending through the casing wall and communicating between the interior of the casing and said third port, means for delivering low pressure fluid into said casing, means for acting on the fluid within the casing to increase its rate of flow from within the casing to the interior of the cylinder block, said means comprising cut outs in said disk-like portions extending radially of said portions and open at the outer periphery of said portions forming slots adapted to be filled with fluid within the casing and to discharge it under centrifugal force, and conduit means adapted to register with one of the said pintle bores to receive high pressure fluid from the pump.

2. An hydraulic pump comprising a casing providing a circular closure, a pintle mounted centrally in the casing, a radial cylinder block, mounted for rotation around said pintle and concentric therewith, means for supplying fluid into said casing between the pintle and said track ring, a track ring, and support means therefor mounted in said casing for rotation about an axis eccentric to the axis of said pintle, and pistons in the cylinders of said block adapted to contact said track ring and to cause it to rotate when said cylinder block is rotating, the space within said casing between said track ring and the casing wall comprising in effect two similar chambers each having its greatest cross sectional area diametrically opposite said pintle axis from said eccentric axis, and a fluid discharge port located in the casing wall at a point diametrically opposite the pintle axis from said eccentric axis and therefore in a position to receive fluid from said chambers respectively in the locality of their greatest cross sectional area, the said support means for said track ring including radially disposed slots opening outwardly into the said space between the track ring and the casing wall, and adapted, when the cylinder block is rotating, to discharge fluid into said space, and means interconnecting said discharge port and the cylinders of said cylinder block.

3. A radial pump comprising a casing, a pintle having two fluid passages extending into said casing, a radial cylinder block mounted for rotation on said pintle, means for driving said cylinder block for rotation about the pintle, track means located within said casing eccentrically with respect to the axes of said pintle and said cylinder block, and support means for said track ring extending from between the cylinder block and the casing to the track ring and having radially extending slots opening outwardly beyond the track ring and adapted to receive fluid and to discharge it by centrifugal force toward the periphery of the casing, means for supplying fluid into the casing, and conduit means including one of said pintle passages for receiving the fluid discharged from said slots and supplying it to the interior of said cylinder block, the other of said pintle passages serving to receive and transfer fluid which has been acted on by the pistons of said cylinder block.

4. An hydraulic pump comprising a casing providing a circular closure, a pintle mounted cen-

trally in the casing, a radial cylinder block, mounted for rotation around said pintle and concentric therewith, a track ring, and support means therefor mounted in said casing for rotation about an axis eccentric to the axis of said pintle, and pistons in the cylinders of said block adapted to contact said track ring and to cause it to rotate when said cylinder block is rotating, the space within said casing between said track ring and the casing wall comprising in effect two similar chambers each having at all times its greatest cross sectional area diametrically opposite said pintle axis from said eccentric axis, and a fluid discharge port located in the casing wall at a point diametrically opposite the pintle axis from said eccentric axis and therefore in a position to receive fluid from said chambers respectively in the locality of their greatest cross sectional area.

5. In a radial pump, a casing, a pintle mounted centrally in the casing, a rotor assembly rotatable within the casing around said pintle, means for supplying propulsion fluid into said casing between the rotor and a track ring, a track ring intermediate the rotor and the casing, rotatably mounted support means for the track ring including outwardly opening radial slots each adapted to collect fluid introduced into the casing and discharge it under centrifugal force toward the peripheral wall of the casing and beyond the track ring, a port in the casing wall located beyond the track ring and on the far side of the rotor axis from the axis of the track ring, and a conduit interconnecting said port and the cylinders of said rotor assembly.

6. A radial pump comprising a casing, a pintle mounted centrally in the casing, a cylinder block mounted for rotation on the pintle and including a number of radial cylinders and pistons in said cylinders respectively, and a track ring assembly positioned between the cylinder block and the casing, eccentrically with respect to the axis of said pintle and said cylinder block, and including a circular track aligned with the cylinders of the cylinder block and adapted to be contacted by the pistons of said cylinders, and means for supporting said track for rotation including hub members positioned on opposite sides of the cylinder block, the respective side walls of said casing being cut away to receive said hub members and provide bearings therefor, and radially extending web portions interconnecting the hubs and the track ring, said webs having cut outs forming slots interconnecting the space between the cylinder block and the track ring and the space between the track ring and the casing, and adapted when the track ring is rotating to discharge oil present within its casing toward the periphery of the casing under centrifugal force, means for introducing oil into the casing through an opening in the casing located substantially in alignment with the inner ends of the said slots, and a discharge passage extending through the casing wall and having its inlet at the periphery of said casing and substantially in alignment with the outer ends of said slots, and having its outlet in communication with the cylinders of the cylinder block.

7. In a pump comprising a casing, a pintle positioned within the casing, a radial cylinder block mounted for rotation around said pintle and concentric therewith, and a track ring rotatable about an axis eccentric to the axis of said pintle, a track assembly characterized by track ring support means including hub means rotatably mounted in the casing and radially extending

means interconnecting the hub means and the track ring, said radially extending means having outwardly opening slots adapted to fill with propulsion fluid present within the casing and discharge it under centrifugal force when said track assembly is rotated.

8. In an hydraulic pump comprising, a casing, a pintle, a cylinder block mounted for rotation on the pintle, and a track ring assembly mounted eccentrically with respect to the axis of the cylinder block intermediate the cylinder block and the casing wall, in which the space between the cylinder block and the casing wall is filled with oil or other propulsion fluid employed, an inlet passage extending through the side wall of the casing to introduce low pressure fluid directly into the casing, an outlet passage leading from the periphery of the casing through the casing wall and adapted to communicate with a conduit in the pintle leading to the cylinders of the rotor, and means within the casing for supercharging the fluid delivered from within the casing through said outlet passage and said pintle to the cylinders of the rotor comprising slotted members forming part of said track ring assembly disposed on opposite sides of said rotor cylinders, between the cylinders and the respective side walls of the casing and serving to support the

track ring, the slots of said members having their inner ends substantially in alignment with said fluid inlet passage, and extending radially of said members to the outer peripheries thereof respectively, and thus serving to receive oil in the casing near its center and discharge it outwardly under centrifugal force against the inner periphery of the casing wall.
